CLAIM

The ornamental design for a telephone ear piece aid, as shown and described.

DESCRIPTION

FIG. 1 is a side elevational view of a telephone ear piece aid showing our new design;

FIG. 2 is a top plan view thereof; and

FIG. 3 is a top front and side perspective view thereof. The broken line showing of a fragmentary telephone handset receiver end is for illustrative purposes only and forms no part of the claimed design.

*Fig.1.**Fig. 2.**Fig. 3.*
